THOMAS SMITH WILSON AND WILLIAM CUNLIFFE, OF GARSTON, LIVERPOOL, ENGLAND,
ASSIGNORS TO WILSON BROTHERS BOBBIN COMPANY, LIMITED, OF GARSTON,
LIVERPOOL, ENGLAND

SHUTTLE FOR LOOMS

Application filed October 12, 1926, Serial No. 141,179, and in Great Britain November 20, 1925.

This invention relates to shuttles for looms adapted for automatic replenishment of filling or weft.

Many forms of self-threading devices for such shuttles have been devised, but all so far produced have either suffered from defects of a more or less serious character or they necessitate a somewhat expensive construction.

10 The present invention is directed to the production of shuttle self-threading devices of very simple construction which are also extremely effective in operation and adapted to minimize thread breakages and to avoid 15 weaving defects liable to arise from the use of self-threading devices, and also to minimize the cost of production of such devices.

Weft threading devices for shuttles which consist of one piece of sheet metal provided 20 with two entry traps are known, but these are not designed for nor effective in forming guides acting automatically in respect of the weft being unwound from bobbins, whether these bobbins be wound either in a clockwise 25 or a counter-clockwise direction, but the traps are more in the nature of traps against upward lift so that they are useless for the purposes of the present invention in automatic weft-filling shuttles.

30 The invention consists in a shuttle self-threading device of sheet metal formed in one piece (apart from the guide eye) and providing two forwardly directed thread-retaining entry traps, one directed from each side 35 of the threading slot.

Referring to the accompanying drawings:

Figure 1 is an elevation, and

40 Figure 2 a plan part of a shuttle containing guiding devices according to one form of the present invention.

Figure 3 is a perspective view of the guiding devices looking from the rear of Figure 2, approximately in the direction indicated by 45 the arrow marked III in Figure 2.

Figure 4 is also a detail view of the guiding devices looking in the direction of the arrow marked IV in Figure 2.

Figure 5 is a plan of the guiding devices practically similar to part of Figure 2, except that the guide is removed from the shuttle.

Figure 6 is an end view of the guiding devices looking approximately in the direction shown by the arrow marked V in Figure 2. 55

In carrying the invention into effect in the form illustrated by way of example, the improved automatic threading shuttle is provided with any usual type of bobbin-holding device (not shown) adapted for automatic 60 replenishment while the other end is formed with an improved type of threading device. This device is adapted to minimize the amount of metal used in this part of the shuttle. The wooden part of the shuttle *a* is formed with a longitudinal threading slot *b* on its face. One side *c* of this slot is smoothed off and acts as a thread guide. On the other side is mounted a sheet metal guide *d* which has a contoured surface *d'*. This 65 guide reinforces the wearing side of the slot and forms the usual forward and inward pointing horn *e* leading to a lateral slot *f* passing the thread *g* to the guide eye *h*. The upper part of the metal horn is bent over 70 and tapers backwardly following the edge of the lateral slot and its forward end projects laterally across the threading slot leaving a small gap only for the thread to pass and enter the lateral slot *f* leading to the eye. 75 The downwardly directed part of the horn also has contoured edges *d*² and *d*³ following the lateral slot and is adapted to guide the thread into the lateral slot *f*. The latter part *d'* of the horn has a suitably placed hole *i* 80 which the thread can enter by a slot. Through the centre of this hole the straight part *j* of an eye element passes and extends across the main threading slot projecting into the other side wall thereof in which it is 85

90

secured. The eye element which may be conveniently of wire forming the guide eye has a projection *k* formed on it. This projection is arranged to follow the curvature of the eye and is disposed in such a position that should the thread retraverse the lateral slot and pass over the main horn into the threading slot it will still be held and guided by the projection and on the next motion of the shuttle it will be automatically threaded again.

The metal guide is thus formed of two main elements *d* and *d'* disposed at about right angles to one another, clearly shown in Figures 3 and 4, particularly one, which may be called the vertical part *d'*, forms one side of the threading slot and has its edge contoured to follow the lateral slot leading into the eye thread guide, while the other, which may be called the horizontal part *d*, has a contour of horn shape which forms the other edge of the same side of the lateral slot leading to the eye. The vertical part has a downwardly extending flap *l* folded on itself to form a securing element extending down into a narrow slot in the shuttle body. This is perforated by holes *m* through which pins or the like *m'* are passed giving a rigid fastening.

The vertical part has also an extension *n* in the form of a plate which projects across the main threading slot. This plate has an orifice *o* registering with the threading slot and it has an entry passage formed in its upper edge leading thereinto. At both edges of this entry passage forwardly directed horns *p* and *p'* are formed and the entry passage itself is disposed angularly (preferably in both planes) across the main threading slot so that when self threading has begun, even although the main horn has not been reached by the thread before reversal of the shuttle motion, guidance of the thread will take place over one or other of these horns during the next forward pass of the shuttle. The self threading will thus operate safely whatever be the hand of winding of the weft bobbins and stripping from the threading device prevented immediately after entry.

In Figure 3, the positions of three threads are shown indicating approximately the direction they take on being trapped in the forward directed traps or the nose of the self-threading metal piece.

A shuttle equipped with the self-threading device above described will be found to present certain advantages; owing to the reduced cutting away of the shuttle end a stronger shuttle structure is obtained; in the event of the thread escaping from the eye and passing back over the main horn the thread will not be broken but will run off until the next pass of the shuttle rethreads it over the horn and replaces it in the eye, the hold of the

thread by the threading device not being lost because the eye trap retains the thread and passes it off until the next throw of the shuttle; while the very simple double trap on entrance avoids the possibility of the device losing the hold of the thread in the event of the thread not passing over the main horn on the first pass or returning therefrom before passing actually into the eye as it is held by one or other of the entrance horns whatever hand of wind exists on the bobbin; the shuttle is lightened owing to the small amount of metal in the self-threading device; and the device is very easily formed by simple pressing and stamping operations from a plain sheet metal blank.

The guide shown with the depending plate *l* has a right-angled part *q* serving to prevent tilting of the guide in the shuttle, but in place of this a flat plate only may be used, so that the upstanding part is not employed.

The construction illustrated includes three thread-retaining traps which may be defined as follows:

(a) A combination of two teeth forming a double entry trap permitting passage of weft between them, but forming guides automatically for the weft being unwound from bobbins either clockwise or counterclockwise. Each of the teeth is adapted to act as a thread-retainer by reason of the concavity behind each tooth.

(b) A nose or guide for transferring longitudinal weft to transverse eye, the trap being substantially longitudinally below the nose and adapted to act as a thread-retainer, the thread passing off at the concavity *e*.

(c) A loop in the transverse eye to prevent by a transverse shoulder or bend the weft after it has entered from passing back from the eye to the nose on backward motion of the shuttle. Here the thread retainer over which the thread passes off is the concavity at *k*.

Having now described our invention what we claim as new and desire to secure by Letters Patent is:

1. In a shuttle in combination, a shuttle self-threading device of sheet metal formed in one piece and providing at its rear end two similarly acting forwardly directed thread-retaining entry traps, one directed from each side of the threading slot and a delivery eye guiding element formed of wire with a transverse trap in its stem.

2. A shuttle for looms adapted for automatic replenishing of filling or weft having in combination three traps, namely (a) a combination of two teeth forming a double entry trap permitting passage of weft between them but forming guides automatically for the weft being unwound from bobbins both clockwise and counter-clockwise, (b) a guide for transferring longitudinal weft to transverse eye formed with a horn such as,

e, adapted to act as a thread retainer substantially longitudinally below the nose, and (e) a wire transverse eye having a loop adapted to prevent by a transverse shoulder 5 the weft after it has entered from passing back from the eye to the nose on backward motion of the shuttle.

In testimony whereof they have signed their names to this specification.

10 THOMAS SMITH WILSON.
WILLIAM CUNLIFFE.
